UNITED STATES PATENT OFFICE.

GEORGE F. SISBOWER, OF EAST ORANGE, NEW JERSEY, ASSIGNOR TO NEW YORK COUCH BED COMPANY, OF NEW YORK, N. Y., A CORPORATION OF NEW YORK.

FOLDING BED.

1,087,613.

Specification of Letters Patent. Patented Feb. 17, 1914.

Application filed November 29, 1912. Serial No. 734,173.

To all whom it may concern:

Be it known that I, GEORGE F. SISBOWER, a citizen of the United States, residing at East Orange, in the county of Essex and State of New Jersey, have invented certain new and useful Improvements in Folding Beds, the following being a full, clear, and exact disclosure of the one form of my invention which I at present deem preferable.

For a detailed description of the present form of my invention, reference may be had to the following specification and to the accompanying drawing forming a part thereof, in which—

Figure 1 shows my folding bed with its parts in an intermediate position, Fig. 2 shows it with its parts in extended position and Fig. 3 in folded or closed position.

Referring to the drawings, A represents one end of a metallic bed frame with an upper curved cross-bar A¹ and a lower straight cross-bar A², it being understood that both ends of the frame are of similar construction. Within this is a horizontally traveling frame B, carrying one half of the spring mattress fabric, with legs and casters at its front edge. Hinged to the rear edge of frame B by the roller junction-plate J is a folding frame, composed of the hinged sections C¹ and C², with a longitudinal rod c which carries the other half of the spring fabric. The roller K at the point of hinge connection between frame B, and the folding frame runs on the upper curved edge of cross-bar A¹ and the plate J overhangs the said cross-bar. At the joint between sections C¹, C² is hinged a leg D having the lower end of an operating bar E hinged thereto. To the junction-plate J is also hinged a U-bar F, to which one edge of the folding mattress M is attached and which is connected to end-frame A by a link G. The upper end of bar E is hinged to the U-bar F. Assuming the bed to be extended as shown in Fig. 2, the U-bar F will be lifted and turned on its hinge to the position shown in Fig. 1. Such movement of the U-bar F will, through the link G and bar E, draw in the traveling frame B and allow the folding frame to double up downwardly and, at the same time, will fold the mattress M and lift the folding leg D. A further movement of the bar F will bring the parts to the closed or folded relation shown in Fig.

3. The reverse operation will open the bed as shown in Fig. 2.

What I claim as new and desire to secure by Letters Patent is:

1. A bed structure comprising a stationary frame, a horizontally traveling frame carrying one portion of the metallic mattress fabric, a folding frame forming an intermediate permanent connection between the stationary frame and the traveling frame and carrying the remaining portion of the mattress fabric, and means for moving said traveling frame, said means also including means for simultaneously acting on the folding frame to fold or unfold the latter.

2. A bed structure comprising a stationary frame, a horizontally traveling frame carrying one portion of the metallic mattress fabric, a folding frame forming an intermediate permanent connection between the stationary frame and the traveling frame and carrying the remaining portion of the mattress fabric, a folding leg connected with said folding section, and means for moving said traveling frame, said means also including means for simultaneously acting on the folding frame and the folding leg to fold or unfold the same.

3. A bed structure comprising a stationary frame, a horizontally traveling frame supported at one edge on the floor and at the other edge on the stationary frame, a folding frame hinged to said stationary frame and also to said traveling frame and forming an intermediate connection between the stationary frame and the traveling frame, and means for moving said traveling frame, said means including means for simultaneously acting on the folding frame to fold or unfold the latter.

4. A bed structure comprising a stationary frame, a horizontally traveling frame carrying one portion of the metallic mattress fabric, a folding frame forming an intermediate permanent connection between the stationary frame and the traveling frame and carrying the remaining portion of the mattress fabric, said folding frame being formed of hinged sections, and means for moving said traveling frame, said means also including means for simultaneously acting on the folding frame to fold or unfold the latter.

5. A bed structure comprising a station-

2
ary frame, a horizontally movable frame supported thereby, a folding frame composed of two hinged sections, one section being hinged to the movable frame and the other section being hinged to the stationary frame, an operating device hinged to the movable frame, a leg hinged to the folding frame, a hinge connection between the leg and the operating device, and means whereby said operating device may be actuated.

6. A bed structure comprising a stationary frame, a movable frame supported thereby, a folding frame hinged to the movable frame and the stationary frame, a leg hinged to the folding frame, an operating device hinged to the movable frame, a hinge connection between the leg and the said operating device, and means whereby said operating device may be actuated.

7. A bed structure comprising a stationary frame provided with a curved supporting bar, a movable frame, a folding frame hinged to the movable frame and to the stationary frame, a roller at the junction of the movable and folding frame engaging the supporting bar, a plate at said junction overlapping the supporting bar, an operating device hinged to the plate, and a link connection between the operating device and the stationary frame. 20
25

In witness whereof I have hereunto set my hand, before two subscribing witnesses, this 27th day of November, 1912.

GEORGE F. SISBOWER.
